UNITED STATES PATENT OFFICE

CARLETON K. STEINS, OF INDIANAPOLIS, INDIANA

THAWING APPARATUS

Application filed November 3, 1928. Serial No. 317,092.

My invention, while relating generally to thawing apparatus, has particular application to a plant for thawing the frozen contents of freight cars, such as coal, ore, sand and the like, to facilitate the removal of such materials from the cars in which they are carried.

One object of my invention is to provide a number of independently heated compartments into which divisions of a train of freight cars may be shunted and confined for thawing, the heating apparatus being located beneath the tracks so that hot air may rise directly to the car compartments with a minimum of heat loss. This arrangement in addition to its advantage in economy of fuel consumption reduces the area of the thawing plant and enables the use of conduits of comparatively short lengths for the circulation of heated air.

A further object of my invention is to simplify the structure of the thawing plant by incorporating the hot air ducts in the foundations for the compartment partitions and thus minimize wasteful dissipation of heat.

Still another and important object of my invention is the provision of an arrangement which permits an efficient and handy system for fueling the heating furnaces and carrying off the ashes therefrom.

While I am aware that thawing plants of various types in which heated air has been used as the thawing medium have been the subject of prior patents and are in present use, my invention is characterized by the novel arrangement and operation of thawing apparatus resulting in marked advantages including more efficient and more uniform heating of the car compartments as will be apparent from the drawings and the description which follows, in which I have illustrated and described a preferred embodiment of the invention and whereof:

Fig. I is a location plan showing the thawing plant and the various tracks leading to it;

Fig. II is a track plan of the floor of the car thawing compartments;

Fig. III is a plan view of the heater and blower room;

Fig. IV is a longitudinal section of the thawing plant;

Fig. V is a cross section of the thawing plant taken along the lines V—V of Fig. II;

Fig. VI is a cross section of the thawing plant taken along the lines VI—VI of Fig. II;

Fig. VII is a cross sectional view of a similar thawing plant with modified details;

Fig. VIII is a longitudinal section of a portion of the thawing plant of Fig. VII showing a hopper car carrying coal for the heaters and means for dumping the coal; and,

Fig. IX is a cross section of an air heating furnace.

Referring particularly to Fig. I, I have shown the thawing plant comprehensively designated by the numeral 1 with a series of tracks 2 for shunting divisions of a train 3 of freight cars into the various compartments of the thawing plant. The track location plan also shows a coal car track 4, an ash car track 5 and a runaround track 6 which will be described more in detail hereinafter.

In Fig. II the track plan of the thawing plant 1 shows the compartments 3 with longitudinal partitions 7 and doors 8 constructed of suitable insulating material so that each compartment may be independently heated.

By virtue of the complete isolation of each compartment from neighboring compartments only a sufficient number of compartments need be heated as are required to house the number of cars the contents of which are to be thawed. The thawing medium preferably employed is hot air supplied at the bottom of the compartments 3 adjacent the rails of their respective tracks 2 by means of tuyères 9 disposed longitudinally of the compartments and substantially distributed throughout their length. Centrally of each compartment return air intakes 10 are provided to conduct air to be reheated back to the heaters 11 and so complete its circulation throughout the compartment.

The arrangement of these heaters 11 is best shown in Fig. III. A basement, comprehensively designated by the numeral 12, running transversely of and beneath the mid-

dle sections of the compartments 3 houses the heaters 11 which are conveniently arranged in staggered formation, there being one heater for each compartment. Adjacent each heater 11 there is shown a motor driven blower 13 is situated on the cold air side of the heater directly beneath a return air intake 10 and adapted to regulate the air flow through the heater. From the hot air delivery side of each heater trunks 14 lead to conduits 15 formed in the foundations 16 which support the partitions 7 as may best be seen from Fig. V. The foundations 16 are perforated at longitudinal intervals to provide tuyères 9 which furnish heated air to the compartments adjacent the rails of the tracks 2. It will be apparent from the description thus far that full advantage is taken of the natural tendency of hot air to rise, and that the direction of flow as indicated by the arrows is from the heaters directly upward through the trunks 14, thence outward through the conduits 15 along the length of each compartment and upward again through the tuyères 9 from whence the hot air is distributed throughout each compartment.

One of the heaters 11 is illustrated in detail in Fig. IX. It comprises a refractory furnace 17 with a grate 18 above which there are a series of flues 19 which lead to a common air trunk 20. The gases from the furnace pass upward through a stack 21 which is situated within a partition or bulkhead 35 7 and which terminates in a chimney 22 above the roof 23 of the thawing plant. Associated with each heater 11 is a blower diagrammatically represented at 13, the construction of which is not material to the invention. 40 The blower 13 supplies the heater 11 with air to be reheated through the trunk 24. An electric motor 25 with a belt drive 26 is shown as the prime mover for operating the blower 13.

45 Referring to Fig. VII, I have shown at the right-hand side of the thawing plant a coal car track 4 with a car 27 thereon, there being a coal pocket 28 beneath the car into which coal for the heaters 11 is dumped. 50 A cut-off gate 29 controls the flow of coal from the pocket 28 into a coal wagon 30 which runs on the narrow gauge track on the floor of the basement. At the left hand side of the thawing plant I have shown an ash car track 5 with a car 31 thereon for carrying off ashes from the heaters 11. Ashes are carried by the wagon 30 to an ash pit 32 from whence they are hoisted in buckets on an ash elevator 33 to a position 55 above the ash car 31, there being a swivel chute 34 for dumping the ashes into the car.

In Fig. VIII, I have shown a coal car 27 of a common type in position for dumping with the coal wagon 30 positioned beneath

the coal pocket 28 to receive coal for fueling the heaters 11. Obviously the arrangement shown can be readily adapted for the transportation and handling of other fuels than coal such as coke or oil.

70 The run-around track 6 serves to allow the passage of a train of cars by the thawing plant when the various other tracks are occupied, and may also be conveniently used for reversing the position of a locomotive 75 on a train from one end to the other.

The operation of my thawing apparatus being apparent from the description need only be briefly described. Initially the train of cars, the contents of which are to be 80 thawed, is separated into divisions which are shunted into the requisite number of compartments. The doors of the compartments are then closed, and in the meanwhile the heaters for those compartments which are occupied are charged and their respective 85 blowers set in operation. The manual labor involved in tending the heaters is materially reduced by the coal and ash handling mechanism previously described.

90 It will be apparent that the arrangement of the constituent parts of the plant is such that heat losses are exceedingly small. The positioning of the heaters directly beneath the compartments to be heated enables the 95 use of conduits of the shortest possible length for conducting air to the compartments and returning it to the blowers. Furthermore, by incorporating conduits in the foundations between the several compartments in the 100 manner shown there is little dissipation of heat to the ground.

While I have illustrated and described one form of my invention, it will be apparent to those skilled in the art that changes may 105 be made in the form of the apparatus disclosed without departing from the spirit of the invention, and that certain features of the apparatus described may sometimes be used with advantage without a corresponding 110 use of other features.

Having thus described my invention, I claim:

1. A thawing apparatus comprising a number of insulated contiguous compartments and tracks for housing divisions of a train of cars carrying material to be thawed, foundations for the longitudinal partitions of said compartments, said longitudinal foundations being formed with conduits therein for supplying heated air to said compartments beneath the track level, a number of air heating furnaces for independently heating said compartments, and located therebeneath, a number of blowers 115 adjacent said furnaces, and return air intakes directly above said blowers and beneath the track level of said compartments.

120 2. A thawing apparatus comprising a number of insulated contiguous compartments 125

with tracks for housing divisions of a train of cars carrying material to be thawed, foundations for the longitudinal partitions of said compartments, said longitudinal foundations being formed with conduits therein for supplying heated air to said compartments beneath the track level, a pit running transversely and centrally of said compartments and situated therebeneath, a number of air heating furnaces in said pit for independently heating said compartments, a like number of blowers adjacent said furnaces and return air intakes directly above said blowers and beneath the track level of said compartments.

5
10
15 In testimony whereof, I have hereunto signed my name at Indianapolis, Ind., this 11th day of October, 1928.

CARLETON K. STEINS.
